UNITED STATES PATENT OFFICE.

KARL FUCHS, OF ORSOVA, RUMANIA.

FRACTIONAL CONDENSER.

Application filed December 8, 1923. Serial No. 679,419.

To all whom it may concern:

Be it known that I, KARL FUCHS, a citizen of the Czechoslovakian Republic, and residing at Rafineria de Petrol, Orsova, 5 Rumania, have invented a certain new and useful Improvement in Fractional Condensers, of which the following is a specification.

For the distillation of crude mineral oils, 10 tar and the like, for the purpose of obtaining commercial derivatives, stills of various construction are used, in which considerable quantities of the combustible fluids are distilled in one operation. These stills are 15 heated by external means or by heating pipes, so that the crude material is easily disintegrated by excessive heat action and not only the heavy and most valuable oil fractions suffer deterioration, but the stills 20 suffer owing to the heated surfaces becoming carbonized.

The object of the present invention is so to carry out the process for the distillation of crude mineral oils, tar and the like that 25 the mineral oil does not distil off by boiling, but is separated from the asphalt by evaporation. For this purpose it is necessary in the first place for the action of the heating medium to be transmitted to the fluid in 30 such a manner that every particle thereof is exposed to the direct action of heat, thus necessitating the employment of far smaller quantities of heat than are usually required. This makes it possible to use a heating medium, 35 the temperature of which can not cause chemical decomposition during distillation. The peculiar way of utilizing and regenerating water vapour as the heating medium forms an essential feature of the 40 invention. Finally the invention provides sure means for the separation of the fractions by cooling the vapours in stages, in dephlegmators, the dephlegmation being effected by the condensate, while it is under 45 the action of the heat of the inflowing, non-condensed light vapour in these dephlegmators. However the vapours and condensate do not come into direct contact with each other, so that the condensate for each 50 dephlegmator is obtained in the desired definite combination.

In the accompanying drawing a plant is shown for carrying out the above process.

Fig. 1 showing diagrammatically the way 55 the evaporation is effected,

Fig. 2 is a diagrammatic elevation of a

combination of superheater, and evaporator and Fig. 2^a shows a vertical section and front view of dephlegmator,

Fig. 3 is a plan view of the superheater 60 and evaporator,

Fig. 4 a diagrammatic section on line 4—4 of Figure 2 with a float arrangement for regulating the inflow of the fluid to be distilled and

Fig. 5 a section on line 5—5 of Figure 2^a,

Fig. 6 shows a modified form of the distilling plant.

In order to make full provision for the conditions obtaining in the evaporation of 70 the fluid, the said fluid is conducted in predetermined quantities regulated by a suitable distributing arrangement to the top pipe of a heating series of pipes and distributed over the whole length of the same, 75 which series of pipes consists of a plurality of horizontal tubes lying one over the other. The fluid drops on to the highest part of the surface of each pipe, so that, owing to adhesion, it forms over the entire surface of 80 the pipe an extremely thin layer, the smallest particles of which are directly exposed to the action of the heating or evaporating surface.

The fluid, which is not evaporated on the 85 surface, of any particular tube will accumulate along the lowest part of the tubular surface and will drip on to the next lower pipe of the series, on which the same sequence of operation takes place.

In Figure 1 the liquid drops from the trough 1, which is provided with a regulatable inlet, through the holes 2 in the bottom of the said trough on to the top of the pipe 3 and is distributed over the entire length 95 of the same. A thin film 4 of liquid will form around the pipe 3 and will evaporate. Any particles that have not been evaporated will accumulate along the lowest part of this pipe, which will act as a distributor 100 for the pipe 5 lying next below it. In this manner the evaporation is repeated until finally asphalt or heavy tar remains as a residue, which is conducted away.

The separate evaporating tubes lying one 105 above the other are combined so as to form heating elements 6 (Fig. 2), the pipes being welded or beaded into two stationary chambers 7 lying opposite one another. In the said chambers partitions 8 are provided, 110 which are so arranged that the superheated steam used as the heating medium always

heats a certain number of pipes uniformly. This is a great advantage for complete evaporation of the evaporable constituents of the crude oil.

As is shown in the drawing a plurality of such heating elements 6 are combined in a vessel 9, which is provided with an outlet pipe 10 for completely draining the said vessel. The accumulated asphalt is tapped off through a siphon-like outlet 11 (Fig. 4).

The crude material enters the apparatus (Fig. 4) coming first into the vessel 12, which is provided with an inspection glass 13 and a float 14, which coacts with the cock 16, for instance by means of a cord or chain 15 having a weight at the other end, for the purpose of regulating the supply.

From the vessel 12 the material flows through the pipe 17 to the troughs 1 mentioned above, from which it drips on to the various heating elements 6 and is evaporated.

For rapidly conducting away the vapors of the heavy oil fractions, which have a low vapor tension, and for enabling the vapors to develop at a low temperature, superheated steam, other inert gas or mineral oil vapors are preferably conveyed at high pressure through pipes 18, lying below each heating element 6, the pipes 18 having perforated walls. For rapidly conveying away the distillation vapors, they are preferably abstracted by suction. In the case of very heavy mineral oils it would appear to be preferable to work at a high vacuum, whereby the evaporating temperature is considerably reduced.

It has been ascertained that for transmitting the heat required for the distillation of a heavy mineral oil two to three times the theoretical amount of superheated steam is required. For this reason superheated steam has not been used as a heating medium for such distillation processes on a large scale. According to the invention, however, the steam is reheated in a superheater as soon as it has performed work in one of the heating elements 6. By this means the consumption of live steam is reduced to such an extent that its employment is far more advantageous than a direct heating of the stills or the employment of heating gases.

For reheating the steam used as the heating medium, for instance four superheaters 19, 20, 21 and 22 are used (Fig. 3). At 23 the live steam flows into the first superheater 19, is brought to the required temperature and flows through the first heating element. The steam thereupon enters the second superheater 20, in which it is again superheated, and flows through the second heating element. In this manner the process is repeated of superheating the steam and causing it to give off its heat, until the steam passes from the last heating element either through the pipes 18 into the evapo-

rating vessel 9 or is used for other purposes.

According to the constructional example shown in Figures 2 and 2^a, the evaporation in the vessel 9 is carried on until asphalt is obtained and the separation of the fraction is effected by cooling the vapors in stages in dephlegmating columns in such a manner that the vapors flowing in the said columns cannot first come into direct contact with the condensate, on the tube sheet X, but are in heat-exchanging relation therewith. After the vapors having left the vessel 9 or having been sucked off from the same, have passed through the liquid separator 24, from which the separated particles of condensed liquid flow off at 25, the vapors pass into a distributing chamber of the dephlegmator 27, from which they are conveyed upwards through the upper pipes 28. The ends of the pipes 28 are provided with slits 29, through which the vapors emerge, whereupon they pass through a filling or porous packing material 30 of the column, which filling rests on a perforated sheet or grid 31. The escaping vapors are cooled by the cooling coil 32 and the condensate drops on to the inclined sheet 33, which causes it to flow on to the upper surface of the cover of the chamber 26 (i. e. the tube sheet X). The condensate thereupon passes through a labyrinth passage formed by suitable partitions 34, at the end of which there is a wall 35, which keeps the condensate at a definite height, to maintain a definite depth of liquid on said tube sheet. The overflowing condensate passes into a separate compartment 36, from which it is conveyed through the siphon-like outflow pipe 37 to the collecting chamber 38 of the dephlegmator and from the latter through the pipe 39 to a cooler or a collecting vessel.

The condensate is thus kept hot by the vapors continuously flowing in and can give off its lighter and more volatile constituents. The same purpose is served by the outflow of the condensate from the dephlegmator being somewhat retarded. By the direct introduction of vapors, any light fractions that may still be present can be driven off. By the successive treatment of the vapors in the dephlegmators of a column the product of distillation can be separated into different fractions, until finally the non-condensed vapors are removed from the last dephlegmator by suction. In each dephlegmator the condensate obtained represents a complete commercial fraction and, by varying the cooling, it is possible to regulate the condensate in each dephlegmator as regards its quality and quantity.

In carrying out the process preferably preheated raw material is used for treatment. For instance the raw material, in order to act at the same time as the cooling medium, is conveyed through the cooling

coils 32 of the dephlegmator, before reaching the vessel 12.

In Figure 6 a modified constructional form of the evaporating apparatus is shown, in which the separate fractions of the vapors are obtained in superposed chambers 40, 41, 42, 43, which are isolated from one another. The action of the heater and its construction are the same as in the first example described, superheated steam being in this case as well conveyed into the lowest pipe of one or more heating pipes 44, the pipes of which are divided into groups in the said chambers, in each of which a fractional distillation of the crude oil is carried out. In the uppermost chamber 43 the quite light constituents are first evaporated, in the second chamber 42 the less light ones, in the third chamber 41 the heavy constituents and in the fourth chamber 40 the very heavy constituents, so that asphalt and heavy tar remain as the residue.

Each chamber is provided with the distributor 45 for distributing the liquid over the entire length of the top pipe of a group of pipes and for causing the said liquid to be evaporated in the manner described above. From one chamber the liquid is conveyed into the next chamber, preferably by siphons 46, the crude fluid being conveyed to the distributor of the chamber 43 from the heater 53, which is heated by the waste steam from the heating elements. In this case as well steam is passed through the pipe 47 into the separate chambers and the vapours are drawn off from the chambers at 48, 49, 50, 51 and unvaporized asphalt at 52.

The evaporator chambers may be placed next to one another instead of over one an-

other in which case the fluid is pumped from one chamber to the next.

What I claim is:—

1. A condenser comprising an upright shell, having a substantially horizontal tube sheet above its bottom and a partition spaced below said tube sheet to form a distributing compartment, a vapor inlet to said compartment, a plurality of upright tubes communicating with said compartment and extending upwardly from said tube sheet, openings in said tubes near the tops thereof, a pervious packing material surrounding the upper parts only of said tubes and extending above the tops of the same, a perforated grid in said shell for supporting the bottom of said packing material a substantial distance above the tube sheet, means for drawing off condensate from said shell above said tube sheet.

2. Apparatus as in claim 1, having, below the perforated grid, and outside of said tubes, an inclined plate for directing the condensate to one side of the condenser, above the tube sheet, baffles upon said tube sheet for causing such condensate to perform a tortuous flow across said tube sheet, to the other side of the condenser, a dam on the said tube sheet, near the last mentioned side of the condenser to maintain over most of said tube sheet, a substantially uniform depth of condensate, a siphon for drawing off the condensate from behind said dam.

In testimony whereof I have signed my name to this specification.

KARL FUCHS.
